UNITED STATES PATENT OFFICE.

JOHN M. CONLEY, OF GOLCONDA, ILLINOIS.

WIRE-CLAMP.

1,065,222.

Specification of Letters Patent. Patented June 17, 1913.

Application filed September 26, 1912. Serial No. 722,550.

To all whom it may concern:

Be it known that I, JOHN M. CONLEY, a citizen of the United States, residing at Golconda, in the county of Pope and State 5 of Illinois, have invented a new and useful Wire-Clamp, of which the following is a specification.

The present invention appertains to clamps, and particularly to those which are 10 employed for clamping woven wire fences, in order that a stretcher or other mechanism may be attached to the clamp for drawing the fence taut.

It is the object of the invention to provide 15 a novel and improved clamp of this character, embodying two clamping bars which may be clamped together over the strands of the fence, the means provided for clamping the bars together being of peculiar construction and operation in order to provide a convenient and efficient clamping action.

This invention also contemplates the provision of a clamp of this class which shall be simple, durable, substantial, inexpensive 25 and compact in construction, as well as convenient and efficient in its use.

To the above and other ends, the present invention resides in the novel construction, arrangement and combination of parts hereinafter set forth and claimed, it being understood that changes in the precise embodiment of invention herein disclosed can be made within the scope of what is claimed 30 without departing from the spirit of the invention.

The preferred embodiment of the invention has been illustrated in the accompanying drawings, wherein like reference characters have been employed to denote corresponding parts, and wherein—

Figure 1 is an elevation of the clamp, parts being broken away. Figs. 2 and 3 are sectional views taken on lines 2—2 and 3—3 of Fig. 1, respectively.

Referring specifically to the drawings, the two clamping bars or members have been indicated by the numerals 4 and 5, the same being constructed of suitable material, preferably wood and being of any desired length 50 and cross section. On the inner face of the bar 5 is secured a pair of longitudinal strips or cleats 6, while the inner face of the bar 5 is provided with a pair of longitudinal grooves 7, which are designed to receive the 55 cleats 6. This arrangement provides a

tongue and groove lock between the clamping bars, or a scarf joint, in order that when the wire strands are clamped between the clamping bars, they will be held securely therebetween, but will not be bent appreciably.

The clamping bar 5 is provided along its length with a series of transverse openings or slots 8, a series of hooks 9 passing slidably through the other bar, and being adapted to pass through the respective openings 8 to engage the outer face of the bar 5. A pair of levers 10 are pivoted to the respective faces of the outer end of each hook 9 and are provided with the eccentrics or cams 70 11 engaging the bar 4, the levers 10 being fulcrumed to the hook by a rivet or other pivot member 12.

A series of bearing plates 13 are secured on the outer face of the clamping bar 4, one 75 of the bearing plates being provided for each hook 9, the hooks passing slidably through the said bearing plates and the bearing plates being provided with outstruck corrugations 14. The hooks pass 80 directly above the corrugations 14, and the eccentrics bear against the said corrugations so as to provide an effective operation.

An actuating or operating bar 15 is pivoted between the ends of the levers 10 by means of the bolts or other pivot members 16, in order that the respective pairs of levers may be swung simultaneously.

Means are provided for locking the levers 90 in depressed position, said means consisting of a stay or link 18 pivoted to the clamping bar 4 adjacent its upper end and provided with a series of apertures 19 at its free end, which apertures are engageable 95 with the stud 17 projecting from the upper lever 10 on one side. Thus, the stay 18 may be attached adjustably to the corresponding lever in order to lock all of the levers in depressed position, so as to retain the bars 100 4 and 5 in clamped position as will herein-after appear.

As a means for swinging the levers 10, there has been provided a handle 20, which is forked at its inner end, as designated by 105 the numeral 21, so as to straddle the actuating rod 15. The ends of the arms of the fork 21 are provided with hooks 22 and the said fork is adapted to rest on a pin 23 carried by the actuating rod 15, the hooks 22 110

being engageable with a loop, staple or the like 24 secured to the outer face of the bar 4.

In use, it being understood that the 5 clamping bars are separated, it will be apparent that the clamping bars may be brought together, over the strands of the fence by inserting the hooks 9 through the respective openings 8 of the clamping bar 10 5, and then permitting the two clamping bars to slide longitudinally relative to each other in order that the hooks engage the outer face of the clamping bar 5. When the hooks 9 are engaged to the clamping 15 bar 5, it being understood that the levers 10 are all swung upward in order to permit the engagement of the hooks with the said clamping bar, the said levers may be depressed in order to effectively clamp the 20 strands of the fence between the clamping bars. This clamping action is facilitated by means of the handle 20, the fork 21 being passed astride the actuating rod 15 and the hooks 22 being engaged with the loop 24, 25 so that the fork may seat on the pin 23 carried by the actuating bar. Now, by swinging the handle 20 downward, the actuating bar 15 will be depressed so as to swing the levers 10 downward simultaneously, thus 30 clamping the two bars 4 and 5 together with great force, and evenly throughout the length thereof. When the clamping bars are sufficiently clamped together, the stay 18 is engaged with the stud 17 of the upper 35 lever 10, which will lock the relative parts in position so that the clamp may be attached to a stretcher or other mechanism for the purpose of drawing the fence taut. It will be apparent, that after the stay has 40 been engaged with the upper lever, the levers cannot be swung, and that when it is desired to release the clamped bars, the stay 18 may be merely disengaged from the said lever 10, in which event, the levers 10 may 45 be readily swung upward to permit the clamping bar 5 to be removed from the hooks 9. It is also preferable to provide a stop 25 on the actuating bar 15 directly below each bolt or pivot member 16, in order 50 that when the levers 10 are swung upward, they will strike the said stops in order to limit the upward movement of the levers, as will be understood.

From the foregoing, taken in connection 55 with the drawings, the advantages and capabilities of the present invention will be apparent, and it will be noted that the objects aimed at are carried out in a satisfactory manner, the present device providing 60 a desirable one for the purposes for which it is designed.

What is claimed is:

1. A clamp embodying two clamping bars,

a series of members slideable through one bar and engageable with the other, a lever 65 pivoted to the outer end of each of the said members and having an eccentric engaging the former bar, an actuating bar pivoted to the free ends of the levers, and a stay pivoted to the former bar and adjustably 70 attachable to one of the said levers.

2. A clamp embodying two clamping bars, a series of bearing plates secured to the outer face of one bar and each having an outstruck corrugation, a hook slideable 75 through each plate above the corrugation, and through the said bar to engage the other bar, a lever pivoted to the outer end of each hook and having an eccentric bearing against the corresponding corrugation, and an actuating bar pivoted to the free ends of the levers.

3. A clamp embodying two clamping bars, one having a series of openings there-through, a series of bearing plates secured 85 to the outer face of the other bar and each having an outstruck corrugation, a hook slideable through each bearing plate above the corrugation and through the said bar, the hooks being adapted to engage through 90 the said openings of the former bar, a pair of levers pivoted to the sides of the outer end of each hook and having eccentrics bearing against the corresponding corrugation, and an actuating bar pivoted between 95 the free ends of the respective levers.

4. A clamp embodying two clamping bars, one having a series of openings there-through, a series of bearing plates secured to the outer face of the other bar and each 100 having an outstruck corrugation, a hook slideable through each bearing plate above the corrugation and through the said bar, the hooks being adapted to engage through the said openings of the former bar, a pair 105 of levers pivoted to the sides of the outer end of each hook and having eccentrics bearing against the corresponding corrugation, an actuating bar pivoted between the free ends of the respective levers, a loop secured on the latter bar, a pin carried by the actuating bar, a handle having a fork adapted to straddle the actuating bar and seat on the said pin, the ends of the fork having hooks to engage the said loop, and a stay 110 pivoted to the latter clamer bar and adjustably attachable with one of the said levers.

In testimony that I claim the foregoing as my own, I have hereto affixed my signature in the presence of two witnesses.

JOHN M. CONLEY.
